UNITED STATES PATENT OFFICE.

ROLAND B. DAY, OF SWARTHMORE, PENNSYLVANIA, ASSIGNOR TO DAY'S PETROLEUM PROCESS CO., INC., A CORPORATION OF ARIZONA.

APPARATUS FOR TREATING HYDROCARBON OILS.

Application filed December 15, 1920. Serial No. 430,874.

To all whom it may concern:

Be it known that I, ROLAND B. DAY, a citizen of the United States, residing at Swarthmore, in the county of Delaware and 5 State of Pennsylvania, have invented certain new and useful Improvements in Apparatus for Treating Hydrocarbon Oils, of which the following is a specification.

This invention relates to apparatus for 10 distilling and cracking hydrocarbon oil material.

One object of the invention is to provide an apparatus for treating either hydrocarbon vapors or liquids which will be capable 15 of applying the required degree of heat to the particular oil material during passage of the oil material through the apparatus.

Another object of the invention is to provide an apparatus in which the working 20 parts cooperate to prevent the formation of deposits of carbon within the apparatus.

One of the features of the invention includes the continuous movement of conveyor apparatus which provides for continuous 25 travel of the oil material from the cooler to the hotter parts of the apparatus, whereby materials requiring a low degree of heat may be cracked and likewise materials requiring a higher degree of heat may be cracked. 30 This feature is contrasted to those forms of apparatus in which the same degree of heat is applied to the exterior of a container to the same degree over the whole container.

Another feature of the invention is directed to the use of conveyor means within 35 tubular retorts and the cooperation of the conveyor means with freely movable elements in the retorts, which elements are of high heat conductivity and preferably metal 40 balls. Steel balls have proved satisfactory and have long life and are worn very slowly. This feature of the invention makes it necessary that the elements be free to move, roll over and tumble around as they are moved 45 through the tubular retorts by the conveyor means, which are preferably screw conveyors substantially filling the bore of the conveyor retorts. By the use of the combined conveyor means and movable elements it 50 has been found that unusually satisfactory results have been obtained in cracking heavy oils. Coke formations have been eliminated by the use of this apparatus, and any free carbon has moved through the tubes and

subsequently passed off through the drain 55 valve provided for residues.

Another feature of the invention includes the use of a conveyor tube connected with the extreme end of the tubular retorts and adapted to carry oil materials and the freely 60 movable elements upward and reintroduce them into the end of the retorts farthest removed from the source of heat, so that oil and metallic balls may travel through the apparatus for a second complete heating op- 65 eration.

Other details and advantages of the apparatus will be described and claimed in the following specification and claims, and illustrated in the accompanying drawings, in 70 which:

Figure 1 is a side elevation of the heating furnace illustrating the exterior drive shafts and showing the outlines of the tubular retorts in dotted lines;

Figure 2 is a view illustrating the relative directions of rotation of the conveyor shafts looking in the direction of the furnace on the section line 2-2 of Figure 1.

Figure 3 is a section taken on the line 80 3-3 of Figure 1 looking in the direction of the arrow and showing the position of the retort tubes in the furnace; and

Figure 4 is a view of the retort tubes with the furnace removed, illustrating the relative directional movement of the materials within the tubes and the movement of the metal balls.

Like reference numerals refer to like parts in the different figures of the drawings.

Referring in detail to the drawings, 1 represents the masonry construction, either concrete, stone or brick, but preferably fire brick, such as will stand severe temperatures. A suitable stack 2 is provided for 95 leading off the furnace fumes, smoke, and gases of combustion. A source of heat is provided by burners 3 located at the lower part of the furnace and fed by suitable pipes 3^a providing liquid or gaseous fuel. The 100 furnace is braced by suitable buck stays 1^a holding the same to a suitable masonry or concrete base. The flame and hot gases from the burner nozzles is projected inwardly and passes upwardly in the furnace, over a centrally positioned partition 4 and downward to ultimately escape through the stack 2. During the upward movement the heat

comes into direct contact with the exterior of a plurality of longitudinally positioned retort tubes, as will be described.

The drawing illustrates three cracking tubes or retort tubes 5, 6 and 7, positioned one above the other and substantially horizontally. Within the tubes 5, 6 and 7 are respective screw conveyors 5^a, 6^a and 7^a, mounted on and adapted to turn with shafts 5^b, 6^b and 7^b, respectively. Suitable journal boxes or stuffing boxes are indicated for the respective shafts at 5^c, 6^c and 7^c. Materials within the tube 5 are passed to the left, referring to Figure 4 and are dropped through the communicating pipe 8 into the end of the tube 6, and similarly, such materials are passed in the opposite direction in the tube 6 and permitted to drop through the communicating pipe 9 to the lowermost tube 7, in which latter the materials are again moved to the left. The direction of travel of the contents of the apparatus is indicated by arrows. Steel balls B are located between each of the flights of the conveyor screws and are freely movable to roll or tumble during the passage of the oil and balls through the retort tubes, and move from the upper to the lower tube and by means of the elevator conveyor screw are lifted from the lowermost retort tube 7 and reintroduced into the upper tube 5. It is necessary that the balls B be of high heat conductivity and that they resist the abrasive wear to which they are subjected by the action of the conveyor screw in moving them through the apparatus. The use of steel balls has proved of advantage over other known forms. Shale has been used within the retort tube and heavy oil added to it for cracking, but shale has proved undesirable for continued work because it very soon pulverizes and wears down to a powder, sticking to the conveyor tube, and if the oil is very tarry, the shale thus combines with the oil to further choke the retorts. Where the shale has not adhered to the screw, but has been converted into dry powder, such powder cannot be re-used again. Steel balls have proved of advantage because of their long life, the cleaning action of the interior of the retort tubes and screws, and because they may roll and tumble within the retort tubes without jamming. Any kind of metal balls would probably exercise the necessary cleaning action, but steel balls combine the necessary hardness for long wear together with high heat conductivity.

Oil and steel balls B discharged from the left hand end of the tube 7 drop downwardly through the communicating pipe 10 into the tube of the elevator conveyor shaft 11, which latter has a conveyor screw 11^a mounted on a shaft 11^b in a manner similar to the mounting of the conveyor screws 5^a, 6^a and 7^a. A stuffing box 11^c is also pro-

vided. At the lower end of the elevator conveyor screw tube 11 is a drain pipe 12 having a suitable valve 12^a and positioned substantially at the lowermost point of the system. Materials raised through the tube 11 are moved to a point near the end of the tube where they are permitted to drop downwardly through the communicating pipe 13 into the extreme right hand end of the upper conveyor tube 5, from which point 75 they are again passed through the apparatus.

At the top of the system of cracking and elevator tubes is positioned a large reservoir for oil which serves as a combined pre-heating chamber, reservoir and expansion chamber. This chamber is indicated by numeral 14, and is provided with an oil inlet pipe 14^a for the admission of untreated oil which may be controlled by a suitable valve, 80 14^b. A series of test drain spigots 14^c are mounted on the chamber at different elevations to determine the height of the oil therein. A pipe 15 at one end of the chamber 14 leads downwardly from the floor of 90 the chamber to the cracking tube 5. At the other end of the chamber 14 is a pipe 16 leading to the upper end of the conveyor tube 11. At the top of the expansion chamber 14 are suitable pipe connections leading to necessary condensers. At 17 is indicated a condenser line governed by a weighted valve. At 18 is indicated another condenser pipe which may lead to a reflux condenser, not shown.

Drive means for driving the shafts 5^b, 6^b, 7^b and 11^b is provided by main drive shaft 19 mounted in suitable bearings 19^a, and driven by a pulley wheel 20, which latter may be operated from any suitable source 105 of power. Referring to Figures 1 and 2, it will be noted that the shaft 19 moves clockwise and turns a sprocket gear 21, which in turn operates a continuous chain 22, which latter extends over sprocket gears 11^d, 7^d, 6^d, and 5^d, which are mounted respectively on the conveyor shafts 11^b, 7^b, 6^b, and 5^b. The arrows in Figure 2 indicate the relative direction of rotation of the sprocket wheels and the conveyor shafts.

Because of the incline of the conveyor shaft 11^b, it is necessary to provide a universal joint in this shaft between the sprocket wheel 11^d and the stuffing box 11^c. This joint is indicated at 11^e in Figure 1, and the lower end of the shaft 11^b is journaled in a fixed bearing 11^f. At the upper end of the conveyor elevator tube 11 is a corresponding universal joint supported by a fixed bearing 11^f mounted on a bracket secured to the main furnace structure. A second drive chain 22^a connects the opposite ends of the drive shaft 19 and the conveyor shafts 5^b, 6^b, 7^b and 11^b.

The apparatus has been satisfactorily op-

erated with retort tubes 5, 6, 7 and 11 of six inch bore, in which a conveyor screw five and three-quarter inches was operated. The flights on the screw were four inches apart, and both tubes and conveyor screws were ten feet long. Oil introduced into the expansion chamber 14 circulated downward to the different tubes and some of the oil and the balls were taken from the lowermost tube and reintroduced into the upper tube. The blast of flame from the burners 3 provided a temperature ranging from about 1000° F. within the lower tube to 750° F. within the lower tube. The temperature at the upper tube was about 200° F. less than in the lower tube, and was approximately 800° F. when the lower tube was at 1000°, and about 550° F. when the lower tube was about 750° F. The difference in temperature between the upper and lower tubes is accounted for in part by the distance from the source of heat and by the fact that fresh oil is introduced into the upper retort tube. This gradual heating has proved advantageous because by this means every particle of oil is at some time within its travel subjected to the degree of temperature best suited for cracking it. Steel balls one inch in diameter have proved serviceable in this apparatus.

The apparatus has been successfully operated at a maximum temperature of 850° F. in the lower parts of the apparatus, and at a pressure of about 75 pounds to the square inch. Remarkably satisfactory yields of gasoline and low boiling hydrocarbons have been obtained by using the apparatus at the above temperature and pressure. Oil was introduced from time to time into the expansion chamber, and withdrawn occasionally through the pipe 12 to remove heavy residues, and substantially continuously through the vapor lines located at the top of the expansion chamber. The apparatus has proved remarkably free from carbon deposits and this may be ascribed in part to the cleaning action of the balls within the apparatus and to their freely movable rolling or tumbling movement, which makes it possible for them to engage the surface of the conveyor tube without travelling in any one fixed path.

The combined cleaning and travelling movement caused by the cooperation of the conveyor screw with the steel balls will operate in the same manner on materials undergoing treatment whether they be liquid, liquid containing foreign material such as earth, or if the material is in part vapor or gases. Heavier materials will be withdrawn through the pipe 12 and the lighter materials will be withdrawn from the top of the expansion chamber 14 as vapors or gases.

As hereinbefore stated, the use of steel balls is preferable, although balls of other

material may be used. Metal stampings have been used, but without the degree of success with which the apparatus has been conducted when balls were used.

What I claim is:

1. Apparatus for treating hydrocarbon materials comprising a tubular treatment chamber, means for heating said chamber, a plurality of cleaner elements in said chamber freely movable therein, and conveyor means within said tubular chamber for moving said cleaner elements lengthwise thereof, said cleaner elements being moved within said chamber but free to roll or tumble therein. 70

2. Apparatus for treating hydrocarbon materials comprising a tubular treatment chamber, means for heating said chamber, a plurality of cleaner elements in said chamber freely movable therein, conveyor means within said tubular chamber for moving said cleaner elements lengthwise thereof, and means to remove said cleaner elements from one end of said chamber and introduce them into the opposite end thereof, said cleaner elements being moved within said chamber lengthwise thereof but free to roll or tumble therein. 80

3. Apparatus for treating hydrocarbon materials comprising a tubular treatment chamber, means for heating said chamber, a plurality of cleaner elements of high heat conductivity in said chamber freely movable therein, and conveyor means within said chamber for moving said cleaner elements lengthwise of said chamber. 90

4. Apparatus for treating hydrocarbon materials comprising a tubular treatment chamber, means for heating said chamber, a plurality of metal ball cleaner elements in said chamber freely movable therein, and conveyor means within said chamber for moving said cleaner elements lengthwise of said chamber. 100

5. Apparatus for treating hydrocarbon materials comprising a tubular treatment chamber, means for heating said chamber, a plurality of metal ball cleaner elements in said chamber freely movable therein, and a screw conveyor within said tubular chamber for moving said metal ball cleaner elements lengthwise of said chamber. 110

6. Apparatus for treating hydrocarbon materials comprising a plurality of substantially horizontal tubular treatment chambers positioned at different levels adjacent chambers communicating with each other by means of a first passageway, means for heating said chambers, an elevator tube constituting a second passageway connecting the lower and upper chambers, and conveyor means in said elevator tube for carrying materials from said lower chamber to said upper chamber. 120

7. Apparatus for treating hydrocarbon

materials comprising a plurality of tubular treatment chambers positioned at different levels and communicating with each other, means for heating said chambers, a plurality of freely movable cleaner elements in said chambers, conveyor means in each of said chambers for moving said cleaner elements lengthwise of said chambers and permitting said elements to move to the next lower chamber, and conveyor means for moving cleaner elements discharged from the lower chamber and reintroducing them into the upper chamber.

8. Apparatus for treating hydrocarbon materials comprising a plurality of tubular treatment chambers positioned at different levels and communicating with each other, means for heating said chambers, a plurality of metal ball cleaner elements in said chambers and freely movable therein, a screw conveyor in each of said chambers for moving said ball cleaner elements lengthwise thereof and permitting said elements to move to the next lower chamber, and screw conveyor means for moving said ball cleaner elements discharged from the lower chamber and reintroducing them into the upper chamber.

9. Apparatus for treating hydrocarbon materials comprising a plurality of tubular treatment chambers positioned at different levels, a communicating pipe at one end of the upper chamber leading from the bottom thereof into the top of the adjacent end of the second chamber next below, a communicating pipe at the opposite end of said second chamber leading from the bottom thereof into the top of the adjacent end of the third chamber next below, a plurality of freely movable metal cleaner elements in said chambers, conveyor means in each of said chambers for moving said cleaner elements lengthwise of said chambers and permitting said cleaner elements to move by gravity through said communicating pipes to the next lower chambers, an elevator conveyor tube communicating with the lower and the upper chambers, conveyor means in said elevator conveyor tube for carrying said cleaner elements from the discharge end of the lower chamber and introducing said elements into said upper chamber, and heating means for said chambers and elevator tube.

55 10. Apparatus for treating hydrocarbon materials comprising a plurality of tubu-

lar treatment chambers positioned at different levels, a communicating pipe at one end of the upper chamber leading from the bottom thereof into the top of the adjacent end of the second chamber next below, a communicating pipe at the opposite end of said second chamber leading from the bottom thereof into the top of the adjacent end of the third chamber next below, a plurality of freely movable metal cleaner elements in said chambers, conveyor means in each of said chambers for moving said cleaner elements lengthwise of said chambers and permitting said cleaner elements to move by gravity through said communicating pipes to the next lower chambers, an elevator conveyor tube communicating with the lower and the upper chambers, conveyor means in said elevator conveyor tube for carrying said cleaner elements from the discharge end of the lower chamber and introducing said elements into said upper chamber, an expansion chamber connected to said upper chamber, and heating means for said apparatus including a furnace structure enclosing said chambers.

11. Apparatus for treating hydrocarbon materials comprising a plurality of tubular treatment chambers positioned at different levels, a communicating pipe at one end of the upper chamber leading from the bottom thereof into the top of the adjacent end of the second chamber next below, a communicating pipe at the opposite end of said second chamber leading from the bottom thereof into the top of the adjacent end of the third chamber next below, a plurality of freely movable metal cleaner elements in said chambers, conveyor means in each of said chambers for moving said cleaner elements lengthwise of said chambers and permitting said cleaner elements to move by gravity through said communicating pipes to the next lower chambers, an elevator conveyor tube communicating with the lower and the upper chambers, conveyor means in said elevator conveyor tube for carrying said cleaner elements from the discharge end of the lower chamber and introducing said elements into said upper chamber, and heating means for said chambers and elevator tube, the conveyor means in adjacent chambers being arranged to move said elements in opposite direction.

In testimony whereof I affix my signature.
ROLAND B. DAY.
